UNITED STATES PATENT OFFICE.

ALFRED PETTER SCHOELLERMAN, OF LAKE PARK, IOWA.

WINDOW.

1,399,323.

Specification of Letters Patent.

Patented Dec. 6, 1921.

Application filed December 28, 1920. Serial No. 433,575.

To all whom it may concern:

Be it known that I, ALFRED P. SCHOELLERMAN, a citizen of the United States, and a resident of Lake Park, in the county of 5 Dickinson and State of Iowa, have invented certain new and useful Improvements in Windows, of which the following is a specification.

The present invention relates to improvements in windows, and has for its object to provide a window which is of simple and durable construction, reliable in operation, and easy and inexpensive to manufacture, and which is especially adapted for use as 10 a sleeping porch or balcony window or basement window as it is substantially rain and water-proof, is easily operable and particularly adapted to be associated with the construction of the building adjacent such parts. 15 Other objects and advantages of the invention reside in certain novel features of construction, combination and arrangement of parts which will be hereinafter more fully described and particularly pointed out in the 20 appended claims, reference being had to the accompanying drawings forming part of this specification, and in which:

Figure 1 is a transverse vertical sectional view of one form of the invention; 30 Fig. 2 is an inside elevational view thereof;

Fig. 3 is a detail view in transverse horizontal section on line 3—3 of Fig. 1;

Fig. 4 is a view in transverse vertical section of a modified form of the invention;

Fig. 5 is a detail view in transverse horizontal section on line 5—5 of Fig. 4;

Fig. 6 is a view in transverse vertical section of another modified form of invention; 40 Fig. 7 is an inside elevational view thereof;

Fig. 8 is a detail view in transverse horizontal section on line 8—8 of Fig. 6; and

Fig. 9 is a fragmentary detail view, partly 45 in section and partly in elevation of the hinge connection employed in one form of the invention.

Referring to the drawings especially to Figs. 1, 2 and 3, it will be seen the invention 50 contemplates a frame 10 which includes side members 11. A sill 12 is associated with the frame at the lower end thereof.

An upper sash designated at 13, and a lower sash designated at 14, are arranged in 55 the frame. The sashes 13 and 14 are of conventional construction embodying side rails

designated at 13^a and 14^a, respectively, top rails designated at 13^b and 14^b, respectively, and bottom rails designated at 13^c and 14^c, respectively. Suitable panes of glass are 60 carried by the rails of each sash.

The upper sash 13 is pivotally connected to the top member of the frame 10 by means of hinges 15 which embody leaves 15^a and 15^b secured to the top member and the top 65 rail 13^b of the sash respectively and pivotally connected to each other by means of the hinge pin 15^c.

The lower sash 14 has its top 14^b pivotally connected to the bottom rail 13^c of the upper 70 sash by means of a hinge designated generally at 16, which includes angle leaves 16^a and 16^b, respectively secured to the exterior side of the bottom rail of the top sash and the side rail of the bottom sash and pivotally connected to each other by means of a hinge pin or pintle 16^c.

Guiding means is provided for the lower end of the sash 14 and includes a stationary plate 17 countersunk in and secured to each 80 side rail 14^a and pivotally connected at 18, to a pivoted guide plate 19 which carries spaced alined guide rollers 20 received in a groove 21 rabbeted or otherwise formed in the side member of the frame. 85

The window is counterbalanced by means of angular arms 22 secured to the lower ends of each of the side rails 14^a of the lower sash and connected by means of ropes or other flexible elements 23 with weights 24 90 operatively arranged within the frame 10. A handle 25 is fixed to the bottom rail of the lower sash and facilitates operation of the window. Sash locks 26 of any suitable type are connected at the upper end of the 95 lower sash to coöperate with the frame to secure the sash closed.

In practice, this form of the invention is especially adapted to be utilized in conjunction with window constructions now employed for it is only necessary to remove the parting strip and the inner guide strip normally employed and then form the groove 21 in the side member of the frame along the line of the parting strip and then 100 embody the invention in the window. In operation if it is desired to open the window, the operator grasps the handle 25 and pulls upwardly thereon. This induces a swinging motion of the sash 13 at the hinges 15 and 105 relative swinging of the sashes at the hinges 16 and also relatively swinging motion be-

tween the lower sash and its pivoted guide plate and in the complete open position the sashes occupy the position, indicated by dotted lines in Fig. 1, at the extreme upper 5 end of the frame thus permitting a full opening of the window without necessitating any special construction of the adjacent portion of the building and without taking up space desirable or ordinarily used for other purposes.

10 In the form of my invention shown in

Figs. 4 and 5, the frame is designated at 30, and the sill designated at 31 is arranged at the lower end of the frame. The upper 15 sash 32 is pivotally connected at its upper end to the top of the frame at the inner side thereof by means of hinges 33 which each include a leaf 33^a fixed to the top of the frame, a leaf 33^b fixed to the top of the sash and a pintle 33^c pivotally securing the leaves of the hinge to each other. The lower 20 sash 34 abuts the lower end of the upper sash 32 and the meeting ends of the upper and lower sashes have an interfitting connection 25 shown in detail in Fig. 9, and consisting of a shoulder 32^a formed on the upper sash and a shoulder 34^a formed on the lower sash, the shoulders being offset and adapted to lie immediately adjacent each 30 other in the closed position of the window. A hinge designated generally at 35 pivotally connects the upper and lower sash and includes a leaf 35^a fixed to the lower end of the upper sash, a leaf 35^b fixed to the shoulder 34^a of the lower sash and a pintle 35^c pivotally connecting the leaves. The lower 35 end of the lower sash carries a stationary guide plate 37 which is countersunk in the side rail of the sash and carries a guide 40 roller 38 operatively arranged in the longitudinal groove 39 provided in each side member of the frame. The window is counterbalanced by means of angular arms 40 arranged at the lower end of the lower 45 sash and connected by means of rods or similar flexible elements 41 to the weights 42 operatively arranged within the frame 30. A handle 43 carried by the lower sash facilitates the manipulation of the window, 50 and a lock of suitable type carried by the top rail of the lower sash co-operates with the frame to secure the sash in closed position.

55 In operation with this form of the invention the outward movement of the upper and lower sashes at their meeting ends is limited by the action of hinges 35 and by the coaction of the shoulders 32^a and 34^a. When the window is opened, the lower sash 60 is elevated by means of the handle 43 and to accommodate this movement the upper sash 32 swings inwardly about its hinges 33 and the lower sash 34 swings inwardly about the hinges 35 and the single guide roller 38. 65 The counterbalancing of the sashes in the

manner described provides for the easy adjustment to any position and for their sustentation in adjusted position.

In the form of my invention shown in Figs. 6 and 7, the window includes a frame 70 50 and a relatively large number of sash sections shown for the sake of illustration as comprising four or two pairs which are designated 51, 52, 53 and 54, the sash sections 51 and 52 comprising the upper pair 75 and the sections 53 and 54 comprising the lower pair. The sash section 51 of the upper pair is hinged to the top of the frame by means of hinges 55 which include a leaf 55^a secured to the frame, a leaf 55^b secured 80 to the top rail of the sash 51 and a hinge pin 55^c pivotally connecting the leaves. The leaf 55^b is fixed to the inner side of the top rail of the sash 51 whereby the sash 51 is constrained to inwardly swinging movement, 85 it being prevented from moving outwardly beyond the position shown in Fig. 6 by engagement of the top rail of the sash with the top of the frame. The sash sections 51 and 52 of the upper pair are pivotally connected 90 to each other by means of hinges 56, each of which includes a leaf 56^a secured to a shoulder 51^a provided on the upper sash 51, a leaf 56^b secured to the top rail of the sash 2 and a hinge pin 56^c pivotally connecting the leaves of the hinge together. A shoulder 52^a is formed on the top rail of the sash section 52 and coacts with the shoulder 51^a, as shown in Fig. 6. The hinges 56 being arranged on the outside of the 100 sash sections give to the sash sections oppositely swinging movement. The upper sash section 53 of the lower pair is pivotally connected to the lower sash section of the upper pair by means of hinges 57 each of 10 which includes a leaf 57^a fixed to the underside of the bottom rail of the sash 52, a leaf 57^b fixed to the upper side of the top rail of the sash 53 and a pintle 57^c pivotally connecting the leaves. The hinges 57 are 11 arranged on the inner side of the sash as shown in the drawings so that they give to the lower pair of sash sections the same character of suspension that the hinges 55 give to the sash sections of the upper pair. 11 The lower sash section 54 is pivotally connected to the sash section 53 by means of hinges 58, each of which includes a leaf 58^a secured to a shoulder 53^a provided on the bottom rail of the sash section 53, a 1 leaf 58^b fixed to the top rail of the sash 54 and a hinge pin 58^c pivotally connecting the leaves. A shoulder 54^a is provided on the top rail of the section 54 and coacts with the shoulder 53^a as shown in the drawings. 1

Guide rollers 59 and 60 are carried by stationary plates 61 and 62 fixed to the sash sections 52 and 54, respectively and these guide pulleys operate in grooves 63 provided in the side members of the frame 1

50. The sash sections are counterbalanced by means of angular arms 64 carried by the lower ends of the sash section 54 and connected by means of flexible elements 65 to 5 the weights 66 operatively arranged within the frame 50. A handle 56^a is provided on the lower sash section and facilitates the operation of the sash section. Sash locks 67 are carried on the sash sections 52 and 10 54 and coöperate with the frame to secure the sash sections in closed position.

In practice, this form of my invention is especially adapted for use with long or high windows and when the window is open, as 15 shown in dotted lines in Fig. 1, the sash sections do not occupy a great degree of space being closely nested and extending over for a comparatively short distance laterally. The arrangement of the guide pulleys of the 20 hinges and of the action of the shoulders and the sections constrain the sections to proper motion and limit them against assuming undesirable positions.

I claim:

25 1. A window of the character described comprising a frame including side members, a top member, a sill arranged at the lower end of said frame, a plurality of sash sections arranged within said frame, hinges 30 connecting the upper of said sash sections to the top member of said frame and constraining said upper sash section to swinging motion, hinges pivotally connecting the other of 35 said sash sections and constraining said other sash sections to swinging movement, guide rollers arranged upon certain of said sash sections, said side members of said frame having grooves operatively receiving 40 said guide rollers, angular arms carried by the lowermost of said sash sections, weights operatively arranged in said frame, flexible

elements connecting said angle arms and said weights, a handle carried by the lowermost of said sash sections and sash locks carried upon certain of said sash sections and 45 coöoperating with said frame to secure said sash sections in closed position.

2. A window of the character described comprising a frame including side members, a top member, a sill arranged at the lower 50 end of said frame, a plurality of sash sections arranged within said frame, hinges connecting the upper of said sash sections to the top member of said frame and constraining said upper sash section to swinging motion, hinges pivotally connecting the other of said sash sections and constraining said other sash sections to swinging movement, guide rollers arranged upon certain of 55 said sash sections, said side members of said frame having grooves operatively receiving said guide rollers, angular arms carried by the lowermost of said sash sections, weights operatively arranged in said frame, and flexible elements connecting said angle arms and 60 said weights.

3. A window of the character described comprising a frame including side members, a top member, a sill arranged at the lower end of said frame, a plurality of sash sections arranged within said frame, hinges connecting the upper of said sash sections to the top member of said frame and constraining said upper sash section to swinging motion, hinges pivotally connecting the other of said sash sections and constraining said other sash sections to swinging movement, and guide rollers arranged upon certain of said sash sections, said side members of said frame having grooves operatively receiving 70 said guide rollers.

ALFRED PETTER SCHOELLERMAN.
